UNITED STATES PATENT OFFICE.

WILLIAM THOM, OF MARION, INDIANA.

FENCE-POST.

1,184,896.

Specification of Letters Patent. Patented May 30, 1916.

Application filed April 23, 1915. Serial No. 23,355.

To all whom it may concern:

Be it known that I, WILLIAM THOM, a citizen of the United States, residing at Marion, in the county of Grant and State of Indiana, have invented certain new and useful Improvements in Fence- Posts, of which the following is a specification.

This invention relates to fence posts which are constructed of concrete, cement or analogous material, and its object is to provide a novel and improved means for attaching the horizontal strands or line wires of the fence to the post, a fastening being provided which enables the strands to be easily and quickly attached and which securely holds the same.

In order that the invention may be better understood, reference is had to the accompanying drawings in which—

Figure 1 is an elevation showing the application of the invention; Fig. 2 is an enlarged vertical section on the line 2—2 of Fig. 1; Fig. 3 is an elevation showing a modification, and Fig. 4 is an enlarged vertical section on the line 4—4 of Fig. 3.

Referring specifically to the drawing, 5 denotes a fence post of cement, concrete or analogous material. To provide a means for attaching the longitudinal wires 6 of the fence, there is provided a stay-wire or rod 7, which is mounted vertically along one of the faces of the post. In the post, near the base thereof, is embedded a curved tube 8, arranged vertically and so positioned that its ends open through the side or face of the post along which the stay-wire extends. In the top of the post is embedded a curved tube 9, also arranged vertically, and so positioned that its bottom 40 end opens through that face of the post through which the ends of the first-mentioned tube open, whereas its upper end opens through the top of the post.

The stay-wire 7 seats at its upper end in 45 the tube 9, and then extends down along the face of the post, and at the base thereof, the stay-wire enters the lower end of the tube 8 and extends upward through the latter to the upper end thereof, from which 50 latter it projects, the small projecting end being bent down over the face of the post.

Intermediate its ends, the stay-wire 7 is held by a staple 10 embedded in the post, the loop or eye of the staple straddling a 55 recess 11 in that face of the post along which the stay-wire extends, and the latter

having an inward bend into said recess and passing through the staple eye. The staple is set so that its eye is inclosed in the recess 11.

The stay-wire 7 is applied by inserting it downward through the tube 9. It is then wrapped once around the upper line wire 6, and passed through the eye of the staple 10, and at the base of the post it is inserted into the tube 8 from the lower end of the latter, and after it is tightened to take up the slack, the end projecting from the upper end of the tube 8 is bent down against the face of the post. The stay-wire can also be wrapped around the bottom one of the line wires 6. The intermediate ones of the line wires lie between the stay-wire and the face of the post and are held against the latter by the stay-wire. 70 A coil 12 may also be made in the stay-wire to take up slack, and to provide a spiral shock-absorber, giving the stay-wire an elastic connection with the line wires capable of expansion and contraction, and 80 one that will yield or contract when any sudden force strikes the fence.

The upper end of the stay-wire 7 is formed into a holder for a top strand 13 of line wire, barb or plain, commonly used 85 on the top of fence posts, said holder comprising opposite curved jaws 14 slightly spaced at their outer ends to permit entry of the strand 13. The jaws are formed by a substantially circular bend in the wire, 90 and having a second circular bend of smaller diameter and located inside the first bend. The free end of the wire extends alongside the main portion of the wire for a short distance, to form with the latter, 95 the shank of the holder. The jaws are resilient and they yield when the strand 13 is inserted, and after the strand passes into the inner bend, the jaws close up and thus prevent the strand from slipping out. The 100 upper end of the tube 9 extends slightly above the top of the post, where it is slightly expanded or spaced from the front to the rear to receive and retain the doubled portions of the wire forming the shank of the 105 holder, the base of the bends forming the jaws of the holder also seating in the enlarged end of the tube. The holder also serves as a head for preventing the upper end of the stay-wire from being drawn 110 down through the tube 9.

The tubes 8 and 9 are preferably made

of copper or other non-corrosive metal, and they are embedded in the post when the same is molded. The tubes add to the strength of the post at the point where connection with the line wires is made, strength here most needed.

- Figs. 3 and 4 show a slight modification. Here the staple 10 is left off, and an intermediate tube 15, similar to the bottom tube 8 hereinbefore described, is employed for holding the stay-wire 7 intermediate its ends. The stay-wire is wrapped around the line wires 6. This structure brings the strain or shock of the fence on the crown of the arched or curved tubes near the center of the post so that there is little or no strain or pressure at the mouth or outer ends of the tubes or near the surface of the post.
- Both structures hereinbefore described afford a simple and efficient means for fastening the line wires to the post, and also provide a holder for a top strand. There are no projecting or protruding staples, screws, plugs, wire clips or similar parts. Any number of line wires can be attached to the post, and when said wires need renewal they can be easily removed by withdrawing the stay-wire, without damage or injury to the post. A single stay-wire holds all the line wires.

The preferred embodiments of the invention have been shown, but it will be evident that various changes and modifications may be made without departure from the spirit and scope of the invention as claimed hereinafter.

I claim:

1. The combination with a fence post having a curved tube embedded therein adjacent to the base and opening at its ends through one side of the post, and a second curved tube embedded in the post at the top thereof, one end of the last-mentioned tube opening through the top of the post, and the other end of said tube opening through the side of the post; of a stay-wire for the line wires of the fence, said stay-wire being mounted vertically on the side of the post through which the aforesaid tubes open, and the respective ends of the stay-wire passing through said tubes, the upper end of the stay-wire having a head engaging the top of the second-mentioned tube, the lower end of the stay-wire passing upward through the first-mentioned tube from the lower end thereof and made fast at the upper end of said tube.

2. The combination with a fence post having a curved tube embedded therein adjacent to the base and opening at its ends through one side of the post, and a second curved tube embedded in the post at the top thereof, one end of the last-mentioned tube opening through the top of the post, and

the other end of said tube opening through the side of the post; of a stay-wire for the line wires of the fence, said stay-wire being mounted vertically on the side of the post through which the aforesaid tubes open, the respective ends of the stay-wire passing through said tubes and being made fast therein, the upper end of the stay-wire projecting from the top of the post and having thereat means for holding a line wire.

3. The combination with a fence post having curved passageways at the top and the base, the base passageway opening at its ends through one side of the post, and the top passageway opening at one end through the top of the post and at the other end through the side of the post; of a stay-wire for the line wires of the fence, said stay-wire being mounted vertically on the side of the post through which the aforesaid passageways open, the respective ends of the stay-wire extending through said passageways, the upper end of the stay-wire having a head engaging the top of the first-mentioned passageway, the lower end of the stay-wire passing upward through the second-mentioned passageway from the lower end thereof, and made fast at the upper end of said passageway.

4. The combination of a fence post having curved passageways at the top and the base, the base passageway opening at its ends through one side of the post, and the top passageway opening at one end through the top of the post and at the other end through the side of the post; of a stay-wire for the line wires of the fence, said stay-wire being mounted vertically on the side of the post through which the aforesaid passageways open, the respective ends of the stay-wire extending through said passageways, the upper end of the stay-wire having a head engaging the top of the first-mentioned passageway, and means for fastening the lower end of the stay-wire in the second-mentioned passageway, the upper end of the stay-wire projecting from the top of the post and having thereat means for holding a line wire.

5. The combination of a fence post having a curved passageway at the top opening at one end through the top of the post and at the other end through the side of the post; of a stay-wire for the line wires of the fence, said stay-wire being mounted vertically on the side of the post and secured thereto, and extending at its upper end through the passageway, the upper end of the stay-wire projecting from the top of the post and having thereat means for holding a line wire.

6. The combination of a fence post having a curved passageway at the top opening at one end through the top of the post and at the other end through the side of the

post; of a stay wire for the line wires of the fence, said stay wire being mounted vertically on the side of the post and secured thereto, and extending at its upper end 5 through the passageway, the upper end of the stay wire projecting from the top of the post, and a line wire holder on the upper projecting end of the stay wire, said holder comprising opposite curved jaws to receive

the line wire, and said jaws being formed 10 integral with the stay wire.

In testimony whereof I affix my signature in presence of two witnesses.

WILLIAM THOM.
